UNITED STATES PATENT OFFICE.

JOSEPH I. KANE, OF LOS ANGELES, AND HENRY W. A. FUHRMANN, OF ALHAMBRA, CALIFORNIA, ASSIGNORS, BY MESNE ASSIGNMENTS, TO EUGENE JOHN PINEAU, OF LOS ANGELES, CALIFORNIA.

ILLUMINATED ELECTRIC FOUNTAIN.

Application filed July 21, 1921. Serial No. 486,390.

To all whom it may concern:

Be it known that we, JOSEPH I. KANE and HENRY W. A. FUHRMANN, citizens of the United States, residing at Los Angeles and at Alhambra, respectively, in the county of Los Angeles and State of California, have invented new and useful Improvements in Illuminated Electric Fountains, of which the following is a specification.

10 Our invention relates to an illuminated electric fountain, the principal object of our invention being to provide a unique and attractive display device in which is combined colored lights and jets of water, and which device provides an interesting, attractive and pleasing article of decoration, that may be utilized in a show window or for decorative purposes on a pedestal, or on a dining table.

20 Further objects of our invention are to provide a relatively simple apparatus that is capable of being readily shifted from one position to another, and, further, to provide an effective and pleasing display device that may be very economically operated.

With the foregoing and other objects in view, our invention consists in certain new and novel features of construction and arrangement of parts that will be hereinafter more fully described and claimed, and illustrated in the accompanying drawings, in which:

Fig. 1 is a vertical section taken through the center of the fountain.

35 Fig. 2 is a horizontal section taken approximately on the line 2—2 of Fig. 1.

Fig. 3 is an enlarged horizontal section taken on the line 3—3 of Fig. 1.

Referring by numerals to the accompanying drawings, 10 designates a ring shaped frame having suitable supporting legs 11, and removably positioned in said frame is a shallow pan or container 12 within which is formed a centrally arranged depression or pocket 13.

Leading radially outward from this pocket 13 is a duct 14, the outer end thereof communicating, by means of a port 15 that is formed in the bottom of the pan 12, with an annular chamber 16 that is formed adjacent to the marginal wall of the pan 12 by an annular partition 17 that is removably positioned within the pan 12 adjacent to its

marginal wall, and said partition being substantially L-shaped in cross section.

55 Formed in the upper portion of this partition 17 is a series of jet openings 18 that are adapted to direct jets of water from the chamber 16 beneath said partition upwardly and inwardly with respect to the axis or center of the pan.

A screw 19 is seated in the bottom of the pan 12 in position to be projected into the port 15, thereby providing simple means for regulating the flow of water from duct 14 65 through port 15, into the annular chamber 16.

Arranged over the pocket 13 is a plate 20 in the center of which is formed an opening 21, and passing through said opening is the 70 vertically disposed hub member 22 of a bladed impeller 23^a that occupies the pocket 13.

Supported upon a suitable framework 24 that is positioned over plate 20 is a small 75 electric motor 25^a, and the upper end of hub 22 is removably secured to the lower end of the armature shaft 26 of said motor.

Enclosing the upper portion of the motor 25 is a housing 27, and arranged therein 80 and secured to the upper end of the armature shaft 26 is a small fan 28, and which latter, in operation, serves to draw air through the field of the motor for the purpose of cooling the same. Located on top of 85 housing 27 is a small electric lamp 29^a.

A hollow dome-shaped member 32^a, of glass or similar transparent material, is positioned over the motor 25^a, lamp 29^a and associated parts, and the lower edge of said 90 dome-shaped member rests upon short posts 33 that project upwardly from the bottom of pan 12.

In the operation, the current is turned on through main line conductor 30^a, and as a 95 result motor 25^a will be operated and lamps 29^a and 66 will be lighted.

As the armature of motor 25^a is rotated, the impeller 23^a will force water from the pocket 13 through duct 14, from thence through port 15 into the annular chamber 16, and, from said annular chamber, the water will discharge in jets through openings 18 and be directed thereby upwardly and inwardly so as to fall onto the top of 100 the transparent dome 32^a; and this water

2
after passing downwardly over the surface of said dome, enters the pan 12 and finally passes back to the pocket 13 that is occupied by impeller 23^a.

5. The rays from lamp 29^a will radiate upwardly and outwardly through the upper portion of dome 32^a and through the jets of water falling thereon, thus producing a pleasing effect.
10. During the operation of the motor, the pressure of the blades of impeller 23^a upon the water in pocket 13 will react through the impeller and through hub 22 to exert a lifting effect on the armature of the motor, thus minimizing the friction between the armature shaft and its bearings.

15. The hub of the impeller 23^a is extended downward through the bottom of its pocket 13 and receives a beveled pinion 47 that meshes with a pinion 48 and the latter being carried on the inner end of a shaft 49 that is journaled in suitably located bearings 50 and which carries on its outer end a beveled pinion 51. This pinion 51 meshes with 20 a corresponding pinion 52 that is secured on the lower end of a vertically disposed shaft 53 and the latter extending upward through a tubular member 54 that rests on the splash plate 34^a and which serves as one 25 of the supporting members for a horizontally disposed plate 55 that occupies a plane a short distance above the top of the transparent dome 32^a.

30. Formed in the center of plate 55, directly above the center of dome 32^a, is an opening that is closed by a plano-convex lens 56, and, journaled on a stud or pin 57 that is seated in plate 55 to one side of the lens 56, is a horizontally disposed circular frame 58 35 that carries a series of segmental sections 59 of differently colored glass or analogous transparent material. The edge of frame 58 is provided with teeth 60, and engaging therewith are the teeth of a pinion 61 that is carried by the upper end of shaft 53.

40. The frame 58 is of such size that the segments 59 of colored glass are adapted to traverse a path immediately above the lens 56. Supported in any suitable manner immediately above the lens 56 is a skeleton frame, comprising a lower ring 62, an upper ring 63 and a series of rods 64 connecting said rings. This frame serves as a support for a vertically disposed cylinder 65 of 45 frosted glass or the like, and arranged within said cylinder is an electric lamp 66.

When the apparatus is operated, motor 25^a drives impeller 23^a to effect a circulation of water in the pan forming the base of the

5. apparatus and forcing said water, in jet 60 form, upwardly onto the dome 32^a. The rotary motion of the motor shaft is transmitted, through shafts 49 and 53, to pinion 61, and from the latter to the rotatably mounted frame 58.

65. As this frame is rotated the segments 59 of colored glass successively pass directly over lens 56 and beneath lamp 66, with the result that differently colored rays of light are successively thrown downward onto the dome and the jets of water thrown thereonto, thereby producing a pleasing and novel effect.

70. The upper portion of this apparatus may, if desired, be covered with an umbrella-shaped canopy 67, and which latter may be formed of transparent or semi-transparent material such as glass, celluloid, or thin fabric.

75. The fan carried by the upper end of the armature shaft of the motor is effective in producing a circulation of air through the chamber beneath the dome that is positioned over the motor, said air being drawn into the dome beneath its lower edge immediately adjacent to the surface of the water, and thus the motor is constantly cooled by the air current while the apparatus is in operation.

80. An illuminated electric fountain of our improved construction is comparatively simple, may be easily and cheaply produced, requires relatively little power for its operation and provides a novel and pleasing decorative structure that may be used for 85 a variety of purposes.

85. Obviously minor changes in the size, form and construction of the various parts of our improved electric fountain may be made and substituted for those herein shown and described without departing from the spirit of our invention, the scope of which is set forth in the appended claim.

90. We claim as our invention:

95. A fountain comprising a transparent housing, a motor operated impeller for spraying water about the housing, illuminating means within the housing, a lens above the housing, a lamp above the lens, rotatable coloring means interposed between 100 the lamp and lens, and means operatively connecting said motor with said coloring means to impart rotation thereto.

105. In testimony whereof we have signed our names to this specification.

JOSEPH I. KANE.
HENRY W. A. FUHRMANN.
